CRYSTAL HOLDER

Walter E. Kuenstler, Cliffside Park, N. J.

Application July 12, 1945, Serial No. 604,550

8 Claims. (Cl. 171—327)

1

This invention relates to crystals of the character employed in radio work, such as crystals of quartz, tourmaline, or other piezo-electric material, and one of the objects of the invention is to provide an improved mounting and housing means of superior construction for crystals of this character.

It has been established that the frequency of a crystal can be lowered by subjecting the crystal to the influence of X-rays and possibly to the action of other rays or forces. In so treating the crystal it has been found necessary in the past to dismantle the crystal assembly and remove the crystal from its holder or container to enable it to receive the influence of the X-rays. An object, therefore, of the present invention is to provide a crystal assembly, including a housing or container, which will permit the crystal to be subjected to the action of X-rays or other influencing rays, while the crystal remains suitably mounted in the base or seating portion of its container, the container being so designed that it clears the central portion of the crystal mounted in it so that the passage of the X-rays directly to the crystal is greatly facilitated.

Another object of the invention is to provide a holder or mounting for a crystal wherein the crystal assembly, consisting of the crystal and electrodes and a pair of spring plates between which the crystal and electrodes are sandwiched, can be handled as a unit and inserted into or removed from the holder as a unit, the holder being so shaped and formed as to permit the crystal assembly to be easily grasped by the fingers and lifted out of the holder whenever required.

Still another object of the invention is to provide a crystal assembly and holder therefor in which the placement of the crystal assembly in the recess in the holder provided for its reception will serve to establish electrical contact between the electrodes and the contact pins with which the holder is provided.

In the accompanying drawing, wherein an embodiment of the invention is shown,

Fig. 1 is a vertical sectional view through a crystal container or casing constructed in accordance with the invention;

Fig. 2 is a sectional view taken at right angles to that of Fig. 1;

Fig. 3 shows the lower half or body portion of a container or housing, with the crystal assembly fitted into the same;

Fig. 4 is a similar view showing the crystal

2

assembly, including spring plates provided with a central aperture to permit treatment of the crystal by X-rays, the crystal assembly being fitted into the recess in the base portion of the container;

Fig. 5 is a view at right angles to that of Fig. 4;

Fig. 6 is a perspective view of a plated crystal, with the plating on the opposite faces of the crystal omitted from the central portion of the crystal to facilitate the treatment of the crystal by X-rays; and

Fig. 7 is a vertical sectional view through the lower half or body portion of the container or casing.

15 In the structure shown, 1 indicates generally the container or casing in which the crystal and its associated elements are contained. This part of the structure is in the form of a two-part container preferably composed of insulating material such as glass, or of any of the other plastic insulations suitable for the purpose. The container or casing 1 includes a lower half consisting of a bottom or base portion 2 in the form of a molded recessed block, and a top member 3 or cover 3, these parts telescopically fitting together to form an enclosure for the crystal and its associated elements to be hereafter described. A metal outside casing, not shown, may be used over or about the insulating casing described, if desired.

18 The bottom or base member 2 of the container is provided with a relatively deep recess or pocket 4 in which the crystal assembly consisting of the crystal, its electrodes, and a pair of spring plates, is contained. Said recess 4 is surrounded by an upstanding wall 5 having outside tapering surfaces. At the base of the outer surface of said wall is a horizontally-disposed shoulder 6. The cover member 3 telescopically fits around the wall

40 5, and disposed between the lower end 7 of the cover member 3 and the shoulder 6 is a gasket or sealing material 8 which is compressed to insure a tight joint between the lower edge of the cover and the shoulder 6. It will be observed that the lower edge of the cover 3 is so shaped that when the sealing material 8 is compressed between it and the surface of the shoulder 6, said sealing material will tend to be forced inwardly and confined in the joint between the cover and shoulder instead of being forced or squeezed out of the joint between the parts of the container.

45 The crystal 10 contained in the container just described, is shown in Fig. 6, and the form there shown is of the so-called "plated" type. That is

to say, metallic electrode surfaces are provided on the opposite faces of the crystal by means of a thin metallic coating or plating 11 applied to said faces, as distinguished from the standard separate metal plates between which a crystal is customarily sandwiched. Thus, when herein referring to "electrodes" I mean to be understood as meaning either the plated coatings applied to the faces of the crystal, or to separate metallic plates between which the crystal is located, for in the present invention either types may be used with complete satisfaction.

To facilitate the treatment of the crystal by X-rays without requiring it to be removed from its holder, I find it desirable to omit the metallic coatings or platings from the central portion of the crystal, as indicated at 12, thereby enabling the comparatively weak application of X-rays to reach and treat the crystal in a minimum of time.

The crystal 10 and its electrodes 11 (either of the plated or separate-plate type) are sandwiched between a pair of spring plates 13 and 14, each of said plates establishing electrical contact with one of the electrodes. Each plate is outwardly arched or bowed, as more clearly seen in Fig. 2, and each plate has leg-extensions 15 bent to form contact points 16 bearing against the electrodes. In placing the crystal assembly, consisting of the crystal and its electrodes, plated or otherwise, disposed adjacent to the faces of the crystal, and the spring plates, within the recess 4 in the container, the spring plates 13 and 14 are compressed slightly between the fingers and the entire assembly is slid into the recess, the lower edge of the crystal coming to rest against the raised portion 22 at the bottom of the recess 9. The tendency of the spring plates to bow will cause them to frictionally engage against the inner surfaces of the wall 5, thus holding the crystal assembly in place.

It will be noted that each of the spring plates 13 and 14 is provided with a longer leg-extension, indicated at 15a, said extension constituting a resilient tongue which comes into contact with one of the contact pins 17 embedded in the base member or bottom 2 of the container. Each pin 17 has an inner terminal or pointed end 18 exposed in the recess 4 so that the act of inserting the crystal assembly into the recess 4 will cause the tongue 15a on one spring plate to contact the inner end 18 of one of the pins 17 and resiliently bear against the same, thus establishing electrical contact therewith. Each of the spring plates is provided with a tongue 15a, and each of said plates establishes contact with one of the pins 17, thus electrically connecting each electrode surface to a pin 17.

In the embodiment of the invention disclosed in Figs. 1 and 4, it will be noted that each of the spring plates 13 and 14 is provided with a central aperture or hole 19, these holes registering with the uncoated surfaces 12 of the crystal. It will be further noted that the walls 5 of the container base 2 are cut away or recessed, as indicated at 20, these recessed wall portions thereby clearing the aperture 19 in the spring plates 13 and 14.

When the crystal assembly is mounted in the recess 4 of the container it will appear as in Fig. 4. The cut-away or recessed portion of the side walls 5 exposes the aperture 19 in the spring plates, and these apertures 19 expose the unplated areas 12 of the crystal so that X-ray treatment of the crystal is greatly facilitated due to the exposure of the central portion of it in the manner ex-

plained. The cover member 3 is provided in its interior with a pair of integral cross-ribs 21, and when the cover member is placed in position on the base, as shown in Figs. 1 and 2, it will compress the sealing material 8, and the ribs 21 will be brought into contact with the upper ends of the upper leg-extensions 15 and will exert downward pressure on them, this pressure serving to urge the two spring tongues 15a against their respective contact pins 17.

In the embodiment of the invention shown in Fig. 3, the spring plates are not provided with the central aperture, although the side walls 5 of the bottom or base member 2 are shown as being recessed at 20, thus exposing the spring plates and a considerable portion of the crystal and electrodes located between the spring plates. In the bringing of a crystal to a final exact frequency, it is necessary for the worker to remove and insert a crystal in its holder a number of times, and with the arrangement shown, the fingers of the worker are easily inserted through the apertures 20 to grasp the spring plates 13 and 14 and the crystal disposed between them, the entire crystal assembly being thus readily lifted out of the recess 4 and replaced therein without the fingers of the worker being brought into contact with the faces of the crystal.

While I have shown several embodiments of the invention, it is obvious that the same is not to be restricted thereto, as many variations may be made without departing from the spirit of the invention. In herein referring to the coated or plated surfaces of the crystal as "electrodes" I wish to be understood as meaning either such coated surfaces or any other metallic or conducting media disposed against or connected to the opposite faces of the crystal. It is also to be understood that the container or casing herein disclosed may be made in various shapes and may be enclosed in an outside metallic or other enclosure, or may be constructed in numerous other ways to meet different climatic and other requirements.

What I claim is:

1. In a crystal holder, a casing having a cup-shaped base provided with a recess for receiving and holding a crystal and associated parts, a cover member for said holder, said recess being defined by side walls above which portions of the crystal and its associated parts project when the cover member is removed, said side walls having recesses permitting access to the projecting parts of the crystal and associated parts to enable the same to be readily engaged and lifted out of the recess in the casing.

2. In a crystal holder, a base portion, a recess formed therein, a crystal and a pair of spring plates in said recess, the crystal being sandwiched between the plates, each plate having a central aperture exposing the central portion of the crystal, the recess being surrounded by walls partly concealing the crystal and spring plates, at least one of said walls having a recess to expose the central aperture in at least one of the spring plates.

3. In a crystal holder, a crystal having its opposite faces metal-coated, said metal coatings being omitted from the central portion of each face of the crystal, a base portion of insulating material having a recess in which the metal-coated crystal is seated, said base portion having walls surrounding the crystal, some of said walls being recessed to thereby expose the uncoated areas of the faces of the crystal.

4. In a crystal assembly, a plated crystal sandwiched between a pair of spring plates, a casing having a base and a cover member, the base having a recess constituting a seat for the crystal and the spring plates, contact pins entering the recess and contacting with the spring plates, each plate having a central aperture, the base having walls extending around the crystal and spring plates, two of said walls being recessed to clear the apertures in the plates, the cover member telescopically fitting over the walls.

5. In a crystal assembly, a holder consisting of a base portion provided with a recess defined by upstanding walls, a plated crystal sandwiched between a pair of spring plates, said crystal and plates being removably fitted in said recess and projecting above the walls, said crystal and plates being removable therefrom as a unit, parts of the walls being recessed to permit finger engagement of the crystal and plates to thereby remove the same from the recess.

6. In a crystal assembly, a holder having a portion formed with a recess, a crystal, electrodes and a pair of spring plates between which the crystal and electrodes are sandwiched removably fitted into said recess, each of the spring plates having a central aperture, the recess being defined by surrounding walls, some of the walls being recessed to thereby clear the central aperture in the plates.

7. In a crystal assembly, a holder having a portion formed with a recess, contact pins in

the holder having ends exposed in the recess, a crystal and electrodes mounted in the recess, spring plates between which the crystal and electrodes are mounted, each of said spring plates having a tongue in contact with the end of one of the contact pins, the recess being defined by surrounding wall portions, some of the wall portions having recesses through which the fingers may be inserted to grasp the spring plates and the crystal between them when it is desired to lift the spring plates and crystal out of the recess.

8. In a crystal assembly, a crystal having both of its faces metal-coated, the coating being omitted from the central portion of each face to thereby expose the crystal and facilitate the treatment of the same by X-rays, a holder having a recess in which the crystal is mounted, parts of the holder around said recess being shaped to clear the central portion of the crystal.
